UNITED STATES PATENT OFFICE.

HOMER E. WEAVER, OF KNOX, PENNSYLVANIA.

ROPE-CUTTING DEVICE.

1,265,561.

Specification of Letters Patent. Patented May 7, 1918.

Application filed August 14, 1917. Serial No. 186,158.

To all whom it may concern:

Be it known that I, HOMER E. WEAVER, a citizen of the United States, residing at Knox, in the county of Clarion and State 5 of Pennsylvania, have invented new and useful Improvements in Rope-Cutting Devices, of which the following is a specification.

This invention relates to a rope cutting 10 device for cutting rope used in boring Artesian and other wells, and for enabling the pieces cut from the rope to be removed from the well.

The invention has for its object to produce 15 a tool of simple and improved construction whereby the rope may be conveniently cut and removed to afford access to the tools at the bottom of the well.

A further object of the invention is to 20 produce a tool of the class described whereby the rope will be severed by an upward pull on the cutting tool, the severed pieces being removable from the well with the tool.

25 With these and other ends in view which will readily appear as the nature of the invention is better understood, the same consists in the improved construction and novel arrangement and combination of parts 30 which will be hereinafter fully described and particularly pointed out in the claims.

In the accompanying drawing has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawing:

Figure 1 is a perspective view of a rope cutting tool constructed in accordance with the invention;

Fig. 2 is a vertical sectional view of the 45 same, taken on the line 2—2 in Fig. 1.

Fig. 3 is a sectional view illustrating the operation of the device before the actual cutting of the rope.

Fig. 4 is a sectional view similar to Fig. 50 3 and showing the parts after severing the rope.

Fig. 5 is a view in side elevation illustrating a modification.

Fig. 6 is a sectional view taken on the 55 line 6—6 in Fig. 5.

Fig. 7 is a horizontal sectional view taken on the line 7—7 in Fig. 2.

Fig. 8 is a plan view of the knife or cutting blade detached.

Corresponding parts in the several figures 60 of the drawing are denoted by like characters of reference.

In the construction of the improved device there is provided a tube 15 of as large a diameter as can be conveniently lowered 65 into the well where it is to be used. The tube is provided near its upper end with a wrench seat 16 and at its upper extremity it has a tool joint 17 consisting of a tapering externally threaded projection of well 70 known form.

The tube 15 at the lower end thereof has a reduced portion producing a wall 18 of substantially semi-circular cross section. Hingedly connected with the semi-circular 75 wall portion is the shank 19 of a knife or cutter 20, said cutter being of substantially circular configuration and having a straight edge portion 21 with which the shank 19 is connected, and having at the side diametrically opposite to the shank 19, a V-shaped recess 22 the side walls of which present cutting edges 23. The diameter of the cutting blade 20 may be substantially equal to or slightly less than the internal 80 diameter of the tube 15, the parts being so proportioned that the cutting blade 20 may be swung upwardly within the semi-circular wall portion forming the reduced lower end of the tube so as to lie within the cross sectional area of said tube. This is for the purpose of permitting a portion of a rope to 85 pass by the cutting blade and to enter the tubular member 15 as will be best understood by reference to Figs. 5 and 6 of the drawing. 90

The cutting blade, however, is free to swing downwardly to the position seen in Figs. 1 and 6 beyond the recessed portion of the tube 15, a stop member 24 being provided to limit the downwardly swinging movement 100 of the cutting blade before it attains a position at ninety degrees with respect to the axis of the tubular member 15, the stop member being preferably arranged so as to intercept the blade when it reaches a position at an angle from sixty to seventy degrees with respect to the axis of the tube. 105

Assuming that a rope has parted in the well that is being bored and that the tools have become wedged or otherwise fastened 110

at the bottom of the well, it becomes necessary to remove the rope before the tools can be fished out. In such case the improved cutting tool is lowered into the well, it being connected by the joint 15 with a lowering element. When the rope indicated at 25 is reached, the rope will push the cutting blade 20 to a substantially upright position and the rope will enter the tube 15 which 10 may be of any desired length. When the rope reaches the top of the tube, the latter can be lowered no further and it is then pulled in an upward direction when the cutting blade, engaging the rope by its V-shaped 15 recess 23, will force the rope outward in the direction of the well bore and, by continued pulling, will cut the rope as seen in Fig. 6. The severed portion of the rope may now be pulled out of the well and the 20 operation repeated until the entire rope length has been disposed of.

It is sometimes desirable to use a cutting tool of a diameter smaller than the bore of the well. One reason for this is to lessen 25 the liability of the tool to become wedged or to stick in the well bore. Another reason is to enable a single tool to be utilized in well bores of different sizes. To enable this to be done I resort to the modified construction illustrated particularly in Figs. 5 and 6 of the drawing. By this modification I secure externally on the tube 15 just above the reduced or cut-away portion 18, a band 40 which may be of a thickness of one-half 35 inch, more or less. Connected with the band 40 is a piece of tube or casing 41 which extends approximately to the lower end of the tube 15, being of a length slightly exceeding that of the reduced or cut-away 40 portion. This piece of tube or casing 41 may be of a diameter closely approximating that of the well bore, but, being compara-

tively of short length, it is not liable to become stuck or wedged in the well bore. 45 When the device is in actual use, the operation of the knife or cutting blade forces the rope that is to be cut, into engagement with the inner face of the tube or casing 41 instead of in direct engagement with the wall of the well bore, the rope being thus 50 effectively severed.

Having thus described the invention what is claimed as new is:

1. In a device of the class described, a tube having a tool joint at its upper end, 55 said tube being reduced at its lower end to produce a semi-circular wall portion, and a cutting blade hingedly supported on said wall portion and foldable within the cross sectional area of the tube. 60

2. In a device of the class described, a tube having a tool joint at its upper end, said tube being reduced at its lower end to produce a semi-circular wall portion, and a cutting blade hingedly supported on said 65 wall portion, and foldable within the cross sectional area of the tube, and a stop member to limit the downwardly and outwardly swinging movement of the cutting blade.

3. In a device of the class described, a 70 tube having a tool joint at its upper end, said tube being reduced at its lower end to produce a semi-circular wall portion, a cutting blade hingedly supported on said wall portion and foldable within the same, 75 a spacing band secured directly above the cut-away portion and a tube or casing secured on said spacing band and extending approximately to the lower end of the first-mentioned tube. 80

In testimony whereof I affix my signature.

HOMER E. WEAVER.
